(57) **CLAIM**

The ornamental design for a portable chest resuscitation simulator for first-aid training as shown and described.

DESCRIPTION

1.1 is a top perspective view of a portable chest resuscitation simulator for first-aid training, showing our new design in a deflated state;

1.2 is a front elevation view thereof;

1.3 is a rear elevation view thereof;

1.4 is a left side elevation view thereof;

1.5 is a right side elevation view thereof;

1.6 is a top plan view thereof;

1.7 is a bottom plan view thereof;

1.8 is a right side elevation view of the portable chest resuscitation simulator for first-aid training in an inflated state.

The evenly dashed lines represent the bounds of the claimed design and the lines in dot-dash style are directed to environment. Both the evenly dashed lines and the dot-dash style lines are for illustrative purposes only and form no part of the claimed design.
